UNITED STATES PATENT OFFICE.

WALTER A. WOOD, OF HONESDALE, PENNSYLVANIA, ASSIGNOR TO
T. B. CLARK & CO., OF SAME PLACE.

DESIGN FOR A GLASS VESSEL.

SPECIFICATION forming part of Design No. 16,720, dated June 1, 1886.

Application filed February 12, 1886. Serial No. 101,736. Term of patent 3½ years.

To all whom it may concern:

Be it known that I, WALTER A. WOOD, a citizen of the United States, residing at Honesdale, in the county of Wayne and State of Pennsylvania, have invented and produced a new and original Design for the Ornamentation of Glass Vessels, of which the following is a specification, reference being had to the accompanying drawing, forming part thereof.

10 In the drawing is represented a bottom view of a fruit-dish containing my design.

The leading or characteristic feature of my new and original design for the ornamentation of vessels or dishes consists in a surface therefor which comprises a group of quadrilateral frusto-pyramidal elevations, *b*, disposed upon the said surface with their bases contiguous to each other, and having upon each of the quadrilateral outer sides of the said group, 20 and adjacent thereto, a quadrilateral group, *a*, composed of eight triangular pyramids disposed upon the surface in pairs, as shown, and with their bases contiguous, the said first-mentioned group of quadrilateral frusto-pyramidal elevations, furthermore, having at each of its corners, filling the right angle between the adjacent groups of triangular pyramids, a group of quadrilateral frusto-pyramidal elevations similar to that first mentioned. At 25 the border or periphery of the dish is disposed a series of fan-shaped scalloped figures, *f*, alternating with the groups of pyramidal elevations, as shown. The upper bases of the individual groups of frusto-pyramidal elevations are further ornamented with alternately disposed patterns, as shown, produced by lines radiating from the center of the base.

and by lines "cross-hatched" on the surface of the alternate base.

What I claim is—

1. A design for the ornamentation of vessels and dishes, which consists in a group of quadrilateral frusto-pyramidal elevations having their bases contiguous to each other, and a group of eight triangular pyramids disposed upon the surface in pairs, as shown, with their bases contiguous, the said groups being repeated indefinitely upon the surface, substantially as described and shown. 40

2. A design for the ornamentation of vessels and dishes, consisting of groups of quadrilateral frusto-pyramidal elevations and groups of triangular pyramidal elevations disposed upon the surface, and a border composed of a series of fan-shaped scalloped sections, all substantially as described and shown. 50

3. A design for the ornamentation of vessels and dishes, composed of groups of quadrilateral frusto-pyramidal elevations alternating with groups of triangular pyramidal elevations, as shown, the individual frusto-pyramidal elevations composing the said first-named groups being alternately ornamented upon their upper bases with radial lines and cross-hatched lines, substantially as described and shown. 60

In testimony whereof I have hereunto set my hand.

WALTER A. WOOD.

In presence of—
T. B. CLARK,
B. I. WOOD.
